Primary Examiner—Janice E. Seeger
Attorney, Agent, or Firm—Dowell & Dowell, P.C.[57] **CLAIM**

The ornamental design for a table leg assembly, as shown and described.

DESCRIPTION

FIG. 1 is a front perspective view of a table leg assembly showing my new design wherein a rear perspective view would be a mirror image;

FIG. 2 is a side elevational view, the opposite side being a mirror image thereof;

FIG. 3 is a top plan view thereof; and,

FIG. 4 is a bottom plan view thereof.
